DESIGN FOR AN AIRPLANE

Vito L. Volpicelli, Scranton, Pa.

Application October 2, 1944, Serial No. 115,549

Term of patent 14 years

(Cl. D71—1)

To all whom it may concern:

Be it known that I, Vito L. Volpicelli, a citizen of the United States, residing at Scranton, in the county of Lackawanna and State of Pennsylvania, have invented a new, original, and ornamental Design for an Airplane, of which the following is a specification, reference being had to the accompanying drawings, forming part thereof.

Figure 1 is a top plan view of an airplane showing my new design,

Figure 2 is a bottom plan view,
Figure 3 is a front elevational view,
Figure 4 is a rear elevational view,
Figure 5 is a side elevational view, and
Figure 6 is a perspective view thereof.

I claim:

The ornamental design for an airplane, as shown.

VITO L. VOLPICELLI.
